UNITED STATES PATENT OFFICE.

WILLIAM LEROY DAVIS, OF BOND, MISSISSIPPI.

SPRING-WHEEL.

1,260,153.

Specification of Letters Patent. Patented Mar. 19, 1918.

Application filed June 12, 1917. Serial No. 174,376.

To all whom it may concern:

Be it known that I, WILLIAM L. DAVIS, a citizen of the United States, residing at Bond, in the county of Stone and State of Mississippi, have invented new and useful Improvements in Spring-Wheels, of which the following is a specification.

This invention relates to improvements in vehicle wheels referring more particularly to wheels obtaining resiliency by the use of springs.

In carrying out the invention my principal purpose is to provide a more efficient disposition of the springs and coöperating parts. Another object is to provide a spring wheel in which dirt is more effectually excluded from the mechanism.

With these and other objects in view I have incorporated my invention in the construction, combination, and arrangement of parts described in the specification below, more particularly set forth in the appended claims, and delineated in the drawings, in which—

25 Figure 1 is a fragmentary section taken on a plane perpendicular to the axis of the wheel, adjacent one side of the bearing blocks 18 as indicated in Fig. 3 by the line 1—1.

30 Fig. 2 is a fragmentary side elevation showing the outer parts of the wheel broken away to expose the springs and adjacent portions of the mechanism.

Fig. 3 is a fragmentary transverse section view through the outer portions of the wheel on the plane indicated by the line 3—3 of Fig. 1.

Fig. 4 shows a detail of the invention.

As shown in the drawings the wheel has 40 an inner rim 1 having spokes 2 attached in any usually employed manner. Attached to the periphery of the rim is an annular channel member 3, for containing the spring elements, having a base 4 bolted or otherwise properly secured to the rim, and laterally spaced outwardly extending flanges or side walls 5 and 6 preferably parallel to each other and at right angles to the base 4. One of the side walls 5 may be formed integrally 45 with the base and for convenient access to the springs the other side wall 6 may be bolted or otherwise detachably engaged on the base 4.

Each side wall is formed with spaced 55 rectangular openings 7 disposed in an annular row which is concentric to the base 4,

and the openings in the two walls are arranged in coinciding relation. Extending between the walls and terminating in the openings are connecting elements constituting spring-pockets 8, each pocket 8 comprising a tube preferably rectangular in section which may be provided with shoulders 9 abutting against the side walls or with any other suitable means for secure retention in position. Radially disposed in each pocket 8 is a compression spring 10 bearing against compression-plates 11 inserted in the pockets 8 for free sliding movement, the plates 11 having the ends protending from the respective openings for a purpose to be hereinafter mentioned. Bearing against the outside of each radial wall 8' of the pockets 8 is a spring 12 extending, preferably tangentially, to bear against a shoe 13 mounted for free movement in a direction to compress the spring; such mounting here shown as projections 14 on the sides of the shoe 13 slidably engaged in guide-slots 15 provided in the side walls 5 and 6. To prevent displacement, the springs 12 may be inserted in sockets 16 attached to the walls 8' of the pockets 8 and shoes 13 or any other suitable means may be employed.

Spaced outwardly from and normally 85 concentric to the side walls 5 and 6 is an outer rim 16' which may have on the periphery a rubber tread 17 for contact with the roadway and is provided on its inner periphery between the adjacent ends of each 90 pair of springs 12 with an inwardly tapered or wedge-shaped bearing-block 18 in face-to-face contact with the shoes 13; whereby the majority of the springs will be compressed in a relative movement of the rims. 95 To enable the resiliency of the springs 10 to take effect a disk-shaped annulus 19 is closely fitted into the rim 16 on each side and is arranged in outward overlapping relation to the corresponding side wall, and 100 formed for receiving the protruding ends of the plates 11 with openings 20 elongated to permit relative rotation of the rims 1 and 16 within the effective range of the springs 12. To retain each annulus 19 in position, 105 it is clampingly engaged between a shoulder 21 which may form an integral part of the rim 16 and a circular side-plate 22 which is detachably secured to the rim 16 adjacent of the annulus by suitable means shown as 110 headed studs 23 inserted in openings provided in each annulus 19 and side plate 22,

and having screw threaded engagement in suitable openings in the rim 16'. A spacing ring 24 may be inserted between each side-plate 22 and the adjacent annulus 19 when desired. The side-plates 22 are further utilized for tightly closing the spring-cavity to exclude dirt and retain lubricants, this being effected in the present instance by bolting or otherwise securing to the rim 1 flanges 25 extending adjacent to and here shown as underlying the side plates 22. The spring cavity is preferably filled with grease, and a felt or other suitable washer 26 is preferably inserted between the side-plate and flange to more perfectly seal the joint.

It is to be understood that the herein described embodiment of my invention is not to be interpreted as in any way limiting the spirit or scope of the invention, such limitation being confined to that indicated by the latitude of the claims.

I claim:

1. In a resilient wheel, an inner rim, an outer rim spaced apart from said inner rim, 25 an annular row of spaced wedge-shaped bearing-blocks on one of said rims, a plurality of spring-supporting elements on the other rim, and a plurality of springs extending between said bearing-blocks and 30 said supporting elements, each spring having one end rigidly engaged with a respective supporting element and the other end slidably engaged against a respective bearing-block.

35 2. In a resilient wheel, an inner rim, an outer rim spaced apart from said inner rim, an annular row of spaced wedge-shaped bearing-blocks on one of said rims, a plurality of spring-supporting elements on the 40 other rim, a plurality of springs extending between said bearing-blocks and said supporting elements, each spring having one end rigidly engaged with a respective supporting element and the other end slidably 45 engaged against a respective bearing-block, and guide means on the last-mentioned rim whereby said springs are restricted to movement tangentially to the last-mentioned rim.

3. In a resilient wheel, an inner rim, an 50 outer rim spaced apart from said inner rim, spaced outwardly extending flanges on said inner rim, each of said flanges formed with a plurality of openings, a plurality of pairs of compression plates extending between 55 said flanges and having their ends projecting outwardly through said openings, spring means between the compression plates of each pair, flanges on said outer rim overlap-

ping said flanges on the inner rim and formed with openings coinciding with the openings 60 in said flanges on the inner rim, said compression plates having their outer ends extending through the last mentioned openings.

4. In a resilient wheel, an inner rim, an 65 outer rim spaced apart from said inner rim, spaced outwardly extending flanges on said inner rim, each of said flanges formed with a plurality of openings, a plurality of pairs of compression plates extending between 70 said flanges and having their ends projecting outwardly through said openings, spring means between the compression plates of each pair, flanges on said outer rim overlapping said flanges on the inner rim and 75 formed with openings coinciding with the openings in said flanges on the inner rim, said compression plates having their outer ends extending through the last mentioned openings, connecting means extending between 80 said flanges on the inner rim, an annular row of bearing blocks on the outer rim, and springs extending between said connecting means and said bearing blocks, 85 each spring having an outer end slidably engaged against a respective bearing block. 5

5. In a resilient wheel, an inner rim, an outer rim spaced apart from said inner rim, spaced outwardly extending flanges on said 90 inner rim, each of said flanges formed with a plurality of openings, a plurality of pairs of compression plates extending between 95 said flanges and having their ends projecting outwardly through said openings, spring means between the compression plates of each pair, flanges on said outer rim overlapping said flanges on the inner rim and 100 formed with openings coinciding with the openings in said flanges on the inner rim, said compression plates having their outer ends extending through the last mentioned openings, connecting means extending between 105 said flanges on the inner rim, an annular row of bearing blocks on the outer rim, springs extending between said connecting means and said bearing blocks, each spring having an outer end slidably engaged against a respective bearing block, guide means on said flanges on the inner rim, and 110 means on the outer ends of the last mentioned springs having engagement with said guide means whereby the last mentioned springs are restricted to movement in one direction relatively to said inner rim.

In testimony whereof I affix my signature,
WILLIAM LEROY DAVIS.
